Primary Examiner — Terry A Wallace(74) *Attorney, Agent, or Firm* — Kutak Rock LLP; Bryan P. Stanley(57) **CLAIM**

The ornamental design for a combination bottle and smartphone holder, as shown and described.

DESCRIPTION

FIG. 1 is a front perspective view of a combination bottle and smartphone holder showing my new design.

FIG. 2 is a side view thereof, the opposite side being a mirror image.

FIG. 3 is a bottom plan view thereof.

FIG. 4 is a top plan view thereof.

FIG. 5 is a front view thereof; and,

FIG. 6 is a rear view thereof.

The broken lines are for illustrative purposes only and form no part of the claimed design.
